FIREDOOR OPERATING MECHANISM

Charles R. Davison, Erie, Pa., assignor to The Standard Stoker Company, Incorporated, a corporation of Delaware

Application October 6, 1937, Serial No. 167,497

9 Claims. (Cl. 110—177)

This invention relates to a firedoor for a furnace and more particularly to power actuated mechanism for opening and closing such door.

An object of the invention is to provide an appliance for actuating a firedoor by fluid pressure, that is simple and compact in construction, efficient and reliable in operation and readily applied to a furnace.

A further object of the invention is to provide a firedoor and operating mechanism therefor, particularly designed for use in connection with a firebox provided with a firing opening, wherein a stoker conduit communicates with the lower portion of the firing opening and the firedoor forms a closure for the upper portion of the firing opening.

Another object of the invention is to provide novel means in a fluid pressure actuated firedoor which decelerates the downward or closing movement of the door and functions to raise the door with little effort.

These and other objects of this invention are described in the following specification and illustrated in the accompanying drawings.

25 In the drawings

Fig. 1 is a central vertical longitudinal section through the rearward portion of a locomotive and its boiler showing the invention, in similar section, and applied thereto;

30 Fig. 2 is a fragmentary end elevation of the locomotive boiler showing the invention applied thereto, with parts in section;

Fig. 3 is a central vertical longitudinal section through the rearward portion of the locomotive and its boiler showing the invention in elevation and applied thereto, parts thereof being broken away and shown in section; and

Fig. 4 is a sectional view on the line 4—4 of Fig. 2.

40 The invention is shown by the drawings as applied to a locomotive A having the usual firebox 10 and the boiler backwall 11 in which is provided the firing opening 12. The locomotive cab deck 13 extends rearwardly from the boiler backwall 11 at a level below the firing opening 12.

45 A stoker is indicated generally at B and comprises a riser conduit 14 having a laterally flaring discharge mouth 15 communicating with the lower portion of the firing opening 12. The riser conduit 14 is securely attached at its discharge mouth 15 to the backwall 11 through angle bars 16. The floor portion 17 of the conduit discharge mouth 15 is preferably made detachable and is provided at its forward end in the firing opening 12. A dis-

tributing plate 19 is in detachable engagement with the distributor head 18. Fuel is elevated through the riser conduit by a screw conveyor 20 and is forced over the distributor head 18 onto the distributing plate 19 from which it is projected in aerial paths over the fire in the firebox by blasts of fluid under pressure emitted from the jet openings 21 in the front face of the distributor head 18.

Bounding the upper portion of the firing opening 12 and secured rigidly to the backwall 11 is a frame 22. Upright plate members 23 are secured to the sides of the frame 22 forming guideways 24 receiving the sides of a door 25 providing for upward and downward sliding movement of the door 25 to uncover and cover the upper portion of the firing opening 12.

The door 25 is power operated and for this purpose a motor cylinder 26, housing a piston 27, is attached at one side of the firing opening to one of the angle bars 16 through a bracket 23. The door 25 has a short link 29 pivotally suspended from a stud 36 projecting from the outer side thereof, and the free end of the link 29 is pivoted to the arm 31 of a lever 32 fulcrumed to a stud 33 on the frame 22 at the upper end of and at one side of the firing opening. The arm 34 of the lever 32 is pivotally connected intermediate the fulcrum and its free end to the stem 35 of the piston 27 by a short link 36. With this arrangement it will be evident that when the piston 27 is forced down, the door 25 is raised to expose the upper portion of the firing opening; and, when the piston 27 is forced up, the door 25 is lowered to form a closure for the upper portion of the firing opening.

The piston 27 is actuated by fluid under pressure, preferably air, and the direction of travel of the piston 27 is controlled by a valve 37 operated by a foot pedal 38. From a suitable source 40 of supply air flows through a pipe 39 and is admitted to the upper end of the piston 27 through the port 40 in the cylinder 26. At the same time air flows from the pipe 39 through a short pipe 41 into the valve 37 forcing the valve member 42 against the valve seat 43, thereby permitting air to flow through the valve 37 into pipe 44 and thence to the under side of the piston 27 through the port 45 in the cylinder 26.

Since the effective area at the lower end of the piston 27 is greater than at the upper end thereof, the piston 27 will be maintained in its raised position as shown in Fig. 2, and as a consequence the door 25 will be retained in its lowered position.

Now, if it is desired to raise the door 25, the foot pedal 38 is depressed thus raising the valve member 42 from the valve seat 43 and closing the inlet port 46. This permits air in the cylinder 26 beneath the piston 27 to exhaust through port 45 into pipe 44 and then through the valve 37 and to atmosphere through the port 47. At the same time air passes through the pipe 39 to the top of the piston 27 forcing it down and with the aid of the counterweight 48 raising the firedoor 25.

The counterweight 48 is pivotally suspended from the free end of lever arm 34 by a link 49. The counterweight 48 is free to move up and down in a sleeve 50 that is pivotally mounted at its lower end for swinging movement about a longitudinally extending pin 51 carried in a bracket 52 rigidly secured to the cab deck 13. The pivotal movement of the sleeve 50 prevents the counterweight 48 from binding in the sleeve, since the counterweight in being raised and lowered also has a slight lateral movement due to the fact that the arm 34, from which the counterweight is suspended, moves in an arc with the stud 33 as a center. A vent 53 is provided in the sleeve 50 adjacent its lower end to permit ingress and egress of air as the counterweight 48 moves upwardly and downwardly in the sleeve 50. A handle 54 on the free end of the arm 31 of lever 32 is provided for manual manipulation of the firedoor 25.

A cushioning arrangement is provided for the piston 27 at the end of each downward and upward stroke. At the beginning of the descent of the piston 27, air will exhaust through ports 45 and 55, causing the piston to descend rapidly. As the piston 27 descends it blanks off the port 55 and air will exhaust solely through port 45, thereby causing the piston 27 to travel more slowly at the end of its downward stroke. At the beginning of the ascent of the piston 27, air will exhaust through ports 49 and 56, causing the piston 27 to ascend rapidly. As the piston 27 ascends it blanks off the port 56 and air will exhaust solely through the port 40, thereby causing the piston to travel more slowly at the end of its upward stroke.

I claim:

1. In a furnace having an upright wall with a firing opening therein and a frame for said opening, the combination of a door mounted for vertical sliding movement on said frame, a lever pivotally connected to said door and extending therefrom in a direction transverse with respect to the direction of travel of said door, said lever being fulcrumed intermediate its ends, a counterweight suspended from the end of said lever opposite that end connected to the door, an upright sleeve mounted at its lower end on a support, said sleeve receiving said counterweight, and power actuated means operatively connected to said lever for swinging said lever about its fulcrum to raise and lower said door.

2. In a furnace having an upright wall with a firing opening therein and a frame for said opening, the combination of a door mounted for vertical sliding movement on said frame, a lever pivotally connected to said door and extending therefrom in a direction transverse with respect to the direction of travel of said door, said lever being fulcrumed intermediate its ends, a counterweight pivotally suspended from the end of said lever opposite that end connected to the door, an upright sleeve pivotally mounted at its lower end on a support, said sleeve receiving said counterweight, and power actuated means operatively

connected to said lever for swinging said lever about its fulcrum to raise and lower said door.

3. In a furnace having an upright wall with a firing opening therein and a frame for said opening, the combination of a door mounted for vertical sliding movement on said frame, a lever pivotally connected to said door and extending therefrom in a direction transverse with respect to the direction of travel of said door, said lever being fulcrumed intermediate its ends, a counterweight pivotally suspended from the end of said lever opposite that end connected to the door, an upright sleeve pivotally mounted at its lower end on a support, said sleeve receiving said counterweight, and power actuated means operatively connected to said lever between its fulcrum and its end remote from the door for swinging said lever about its fulcrum to raise and lower said door.

4. In a furnace having an upright wall with a firing opening therein and a frame for said opening, the combination of a door mounted for vertical sliding movement on said frame, a lever pivotally connected to said door and extending therefrom in a direction transverse with respect to the direction of travel of said door, said lever being fulcrumed intermediate its ends, an upright sleeve pivotally mounted at its lower end on a support, a counterweight in said sleeve slideable axially thereof, a link pivotally connected at one end to the end of said lever remote from said door and pivotally connected at its other end to said counterweight, and power actuated means operatively connected to said lever for swinging said lever about its fulcrum to raise and lower said door.

5. In a locomotive having a cab deck and a firebox provided with a backwall having a firing opening therein, the combination of a stoker fuel conduit communicating with the lower portion of said firing opening, a vertically sliding door for closing and exposing the upper portion of said firing opening, a lever pivotally connected to said door and extending therefrom in a direction transverse with respect to the direction of travel of said door, said lever being fulcrumed intermediate its ends, a counterweight suspended from the end of said lever opposite that end connected to the door, an upright sleeve mounted at its lower end on said cab deck, said sleeve receiving said counterweight, and power actuated means operatively connected to said lever for swinging said lever about its fulcrum to raise and lower said door.

6. In a locomotive having a cab deck and a firebox provided with a backwall having a firing opening therein, the combination of a stoker fuel conduit communicating with the lower portion of said firing opening, a vertically sliding door for closing and exposing the upper portion of said firing opening, a lever pivotally connected to said door and extending therefrom in a direction transverse with respect to the direction of travel of said door, said lever being fulcrumed intermediate its ends, a counterweight pivotally suspended from the end of said lever opposite that end connected to the door, an upright sleeve pivotally mounted at its lower end on said cab deck, said sleeve receiving said counterweight, and power actuated means operatively connected to said lever for swinging said lever about its fulcrum to raise and lower said door.

7. In a furnace having an upright wall with a firing opening therein and a frame for said opening, the combination of a door mounted for ver-

tical sliding movement on said frame, a lever pivotally connected to said door and extending therefrom in a direction transverse with respect to the direction of travel of said door, said lever being fulcrumed intermediate its ends, a counterweight pivotally suspended from the end of said lever opposite that end connected to the door, means for limiting lateral swinging movement of said pivotally suspended counterweight, and means for swinging said lever about its fulcrum to raise and lower said door.

8. In a locomotive having a cab deck and a firebox provided with a backwall having a firing opening therein, the combination of a stoker fuel conduit communicating with the lower portion of said firing opening, a vertically sliding door for closing and exposing the upper portion of said firing opening, a lever pivotally connected to said door and extending therefrom in a direction transverse with respect to the direction of travel of said door, said lever being fulcrumed intermediate its ends, a counterweight pivotally

suspended from the end of said lever opposite that end connected to the door, means supported by the locomotive for limiting lateral swinging movement of said pivotally supported counterweight, and means for swinging said lever about its fulcrum to raise and lower said door. 5

9. In a furnace having an upright wall with a firing opening therein and a frame for said opening, the combination of a door mounted for vertical sliding movement on said frame, a lever pivotally connected to said door and extending therefrom in a direction transverse with respect to the direction of travel of said door, said lever being fulcrumed intermediate its ends, a counterweight suspended from the end of said lever opposite that end connected to the door, an upright sleeve mounted at its lower end on a support, said sleeve receiving said counterweight, and means for swinging said lever about its fulcrum to raise and lower said door. 10 15 20
